FLUORESCENT TUBE LIGHTING FIXTURE

Morris B. Beck, Lawrence, N. Y.

Application November 16, 1940, Serial No. 365,852

3 Claims. (Cl. 240—78)

This invention relates generally to lighting fixtures, and more particularly to lighting fixtures of the semi-indirect type, that is, fixtures in which one part of the luminous output passes directly and without reflection to the working plane, while another part reaches the working plane only after reflection.

My invention relates particularly to a fixture employing fluorescent tubes as the light source. For this reason my invention has been disclosed as employing such light source; it will be understood, however, that features of my invention may serve advantageously with other types of light source.

The general object of my invention is the provision of a lighting fixture which is compact, simple in construction and inexpensive to make and maintain and which affords effective light distribution, and in which the efficiency is high, due to the minimization of losses such as absorption losses where fluorescent tubes are used.

Among the more particular objects of my invention is the provision of a fluorescent lighting tube fixture which is arranged in relatively close proximity to the ceiling but in which nevertheless effective and uniform light distribution is attained, and in which, further, effective means for reducing glare is provided.

Another object of my invention is the provision in a fluorescent tube lighting fixture in which a fluorescent tube is positioned in relatively close proximity to a surface such as a ceiling, of means for dividing the luminous output of said tube into portions directed respectively toward and away from said surface, the division being effected substantially by a plane inclined to said surface.

Among the more particular objects of my invention is further the provision in a fluorescent tube lighting fixture of means for dividing the light flux of a fluorescent tube arranged in parallel relation to a reflecting surface, such as a wall or ceiling, in such a manner that a portion thereof will be directed toward the said surface, but in general at an angle thereto, so that the distribution of light on said surface is asymmetrical relatively to a plane perpendicular to the surface and passing through the tube axis, while the remainder of the light flux is directed away from said surface, the distribution being also asymmetric relatively to the aforesaid plane.

Another object of my invention relates to the provision in a lighting fixture comprising a plurality of fluorescent tubes arranged in parallel relation to each other and to a surface, and

said tubes being arranged in groups, of means associated with each of said groups so as to secure the asymmetric distribution described in the foregoing paragraph, and said groups being so positioned that the light flux from the two groups will interact in a predetermined manner. In particular it is an object of my invention to arrange two such groups so that the light flux from each group is divided into two portions, the line of separation or division between these two portions being located in a plane inclined to said surface, and these planes for the two groups meeting at an angle the apex of which is directed towards the surface.

15 It is also an object of my invention to provide in a lighting fixture of the character described means for eliminating glare from the fixture.

These objects and such other objects, as will hereinafter appear or be pointed out, are attained in the illustrative embodiments of my invention shown in the drawings, in which:

Figure 1 is a side elevational view of a lighting fixture constructed in accordance with my invention;

25 Figure 2 is a bottom plan view thereof;

Figure 3 is an end elevational view thereof;

Figure 4 is a transverse sectional view substantially on the line 4—4 of Figure 1, looking in the direction of the arrows;

30 Figure 5 is a sectional view on an enlarged scale taken substantially in the plane indicated by the line 5—5 of Figure 3, looking in the direction of the arrows;

Figure 6 is a transverse sectional view corresponding to a portion of Figure 4, but on an enlarged scale, and showing a modified form of my invention;

35 Figure 7 is a fragmentary view taken substantially in the plane indicated by the line 7—7 of Figure 6; and

Figure 8 is a diagrammatic view illustrating the distribution of light from a fixture of the type shown in Figures 1 to 5 inclusive.

I will now proceed to describe the details of 45 construction of the illustrated embodiments wherein brackets B—1 and B—2 are shown supporting the ends of the tubes F—1 and F—2, and similar brackets B—3 and B—4 are shown supporting the ends of the tubes F—3 and F—4.

50 These brackets extend downwardly and laterally from a canopy C which may be supported from the ceiling, and which has reflecting surfaces 10 and 11 provided at its side and reflecting surfaces 12 and 13 disposed on its bottom portion. Within the hollow of the canopy C may

be disposed the conventional auxiliary apparatus. It will be observed that the reflecting surfaces 10 and 11 are concavely contoured in transverse section.

The brackets B-1 and B-2 may be made hollow as shown in Figure 5, as by being constructed of an inner shell 14 over the side portions 15 of which fits an outer shell 16. This produces a passageway between the shells through which the wiring 17 from the sockets 18, carried by the shell 14 and in which the tubes are mounted, may be led into the canopy C.

Intermediate the fluorescent tubes F-1 and F-2 is shown a member 19 of generally diamond shaped cross-section, which serves to connect the brackets B-1 and B-2, and the outer surfaces of which are formed as reflectors adapted to reflect the light from the tubes. A similar reflecting and connecting member is positioned between the fluorescent tubes F-3 and F-4 and performs a similar function.

Reflecting and supporting members 21 and 22 serve similarly to connect the end portions respectively of brackets B-1 and B-2 and brackets B-3 and B-4, while their inner surfaces act as reflectors. These members also act as glare shields, as will be more fully explained herein-after.

Considering the fluorescent tube F-1 and the adjacent reflecting members 19 and 21, it will be observed that the cross-section of these members is generally diamond shaped and that their axes lie in the same plane as the axis of the fluorescent tube, and, further, that a pair of opposed apices of said reflecting members also lie in said plane.

The surface of the fluorescent tube F-1 will consequently be divided substantially into two portions by the adjacent apices 19a and 21a of the reflecting members 19 and 21, and this division will be more nearly effected the closer these apices lie to the fluorescent tube surface. As a result the light flux of the fluorescent tube F-1 will also be divided substantially into two portions, because the light emission in a fluorescent tube takes place at the inner surface of the glass tube.

While theory would seem to indicate that close contact of the apices with the wall of the fluorescent tube is desirable, in practice, due to irregularities and inaccuracies in the parts, and the requirement of liberal tolerances so as to keep manufacturing costs within reasonable limits, it is found that a slight spacing between the apices and the tube wall is not merely required but is also desirable. I have further found that a slight rounding off of the apices is desirable, as shown in the drawings.

The light flux emitted above the apices 19a and 21a must remain above the plane of the fluorescent tube axis, that below the said apices must remain below the said plane.

The reflecting walls of the members 19 and 21, which are inclined to the said plane, and which furthermore may be slightly concaved so as to secure parabolic reflection will serve to direct the light flux away from the aforementioned plane.

The distance between the vertically spaced apices of the member 19 is preferably made equal to the diameter of the fluorescent tubes F-1 and F-2 so that no light from one of these fluorescent tubes can pass into the other tube. No absorption losses due to this cause can therefore take place.

By reference to Figure 5 it will be observed that

the reflecting and supporting member 21 has been shown of hollow tubular construction, a plug 21b being shown secured within its end portion, and this plug may be secured to the shell 14 in any suitable or preferred manner, as by a screw 21c. Obviously this construction combines lightness in weight with sufficient strength, where a suitable material is used. It is understood, of course, that the other reflecting members 19, 20 and 22 may be of similar construction.

The distance between the vertically spaced apices of the tubes 21 and 22, which do not function to prevent absorption losses is determined mainly by the function of these tubes as glare shields. For the sake of uniformity of appearance and also because of simplification of manufacture, this dimension may be, as shown in the drawings, the same for tubes 21 and 22 as it is for tubes 19 and 20.

20 The reflecting surfaces 12 and 13 function to direct the light from the respective tubes F-2 and F-3 downwardly as far as possible and without redirecting it into the tubes. For this purpose they are appropriately curved, as shown.

25 Attention is now invited to Figure 8 which attempts, diagrammatically, to indicate the light distribution that is obtained with a fixture of the type just described. The fixture is shown diagrammatically in transverse section, and the distribution in a plane transverse to the fixture is shown. This distribution is representative of the distribution of the fixture and gives an adequate idea of its functioning.

30 It will be observed in general, as has already been pointed out, that since the plane dividing the light flux from the tubes F-1 and F-2 is inclined to the horizontal, one portion of the light flux will be thrown upwardly against the ceiling at an angle thereto, and due to this angular inclination of the light flux to the ceiling it will be reflected at an angle downwardly and laterally and away from the fixture, instead of directly downwardly as would be the case if the plane of the axes of fluorescent tubes F-1 and F-2 were horizontal. The light flux on the ceiling is distributed asymmetrically and the same is true of the distribution in the working plane or on the floor after reflection. A further effect of this asymmetric distribution is that the greater portion of the light flux will not strike the canopy C.

35 Another portion of light flux will be thrown downwardly but also generally at an angle to the vertical. The flux proceeding directly from the tubes F-1 and F-2 will diverge in a downward direction; this divergence will be limited by the reflecting members 19 and 21 which will divert rays striking them in a direction more or less perpendicular to the said plane containing the axes of tubes F-1 and F-2, that is in a downward direction but at an angle to the vertical which leads them beneath the other set of tubes F-3 and F-4.

40 The reflecting surface 12, as already stated, is preferably designed so as to reflect as much of the light from the tube F-2 as possible in a downward direction, and reflection back into the tube is avoided as much as possible since such reflection back into the tube causes a loss of light due to the absorption of the reflected rays.

45 The action that has been described for the tubes F-1 and F-2 is identical with that of the tubes F-3 and F-4, except of course that the reflection and light emission occur at angles to the vertical that are opposite to the angles at

which the light from the tubes F-1 and F-2 is distributed.

The foregoing general discussion will be made more clear by a detailed study of Figure 8, in which the light distribution for the tubes F-3 and F-4 has been suggested by selected rays. In said figure is shown the ceiling in section, which has the lighting fixture carrying tubes F-1, F-2, F-3 and F-4 mounted thereon, and below the ceiling is shown the floor, in section, and above the floor the working plane.

The light ray 30 indicates roughly the limit to the right, of direct rays from the fluorescent tube F-3; its point of intersection with the working plane is not shown because it falls outside the limits of the figure. The light ray 31, which pierces the working plane 32 and strikes the floor at 33, represents roughly the limit, to the left, of the direct rays from the tube F-4. The limits at both sides, of the rays reflected from the reflecting members 20 and 22, and from the reflecting surface 13, is indicated approximately by the rays 34 and 35, these rays piercing the working plane respectively at the points 36 and 37 and striking the floor at 38 and 39.

Thus far only rays passing downwardly have been described. Upwardly moving rays will now be discussed. At 40 and 41 are indicated light rays proceeding respectively from the tubes F-3 and F-4 and directly striking the ceiling, from which they are reflected as rays 42 and 43 respectively, and these rays mark approximately the limits, at both sides, of the rays that proceed directly from the tube F-3 and F-4 to the ceiling. The intersection of the ray 42 with the working plane lies outside of the diagram, and gives an indication of the spread of the light flux from the fixture. The intersection of ray 43 with the working plane is shown at 43a. Rays 44 and 45 represent rays intermediate the limiting rays 40 and 41. Their reflections from the ceiling are the rays 46 and 47 respectively, the latter piercing the working plane at 48.

At 49 is shown a ray proceeding from the tube F-4 and striking the reflecting surface 11 on the side wall of the canopy C. This ray will be reflected from the surface 11 as the ray 50.

The effect of the reflecting members 20 and 22 on the tube F-4 is indicated by the limiting rays 51 and 52 which strike the ceiling and are reflected therefrom in the form of rays 53 and 54 respectively which pierce the working plane at the points 55 and 56 respectively.

It will be observed that light thrown upwardly and laterally from tube F-3 and F-4 will be reflected downwardly and laterally to the left of the fixture, while light proceeding downwardly from the tubes F-3 and F-4 will travel downwardly and laterally to the right and underneath the tubes F-1 and F-2.

It is to be understood that the light distribution of the tubes F-1 and F-2 will be similar to that described for the tubes F-3 and F-4, but the lateral component of movement of the light will be in the opposite direction, from that described for the tubes F-3 and F-4.

In this way it will be seen that the two sets of tubes supplement as well as augment each other in their illuminating action. Any lack of uniformity in the illumination obtained on the working plane by any one fixture will be corrected more or less by adjacent fixtures, which are suitably spaced from each other for that purpose.

The second requirement for efficient illumina-

tion is that relating to protection against glare. It will be observed from Figure 8 that to an observer situated laterally of the fixture the reflecting members 21 and 22 serve to shield the fluorescent tubes from the direct gaze of the observer in certain positions. To increase their shielding effect they may be made wider in a vertical direction. As the observer approaches the area directly underneath the fixture the inner reflecting tubes 19 and 20 contribute to the shielding effect, although complete shielding by these means cannot be obtained. However, since an observer positioned underneath the fixture will seldom look upwardly at an angle at which he will look directly into the fluorescent tubes additional shielding may in many cases be dispensed with.

Where, however, such additional shielding is necessary, I may provide a system of louvers as indicated in Figures 6 and 7 by way of example.

In Figure 6 is shown a portion of a bracket P-1, corresponding to bracket B-1, on which are mounted fluorescent tubes G-1 and G-2, corresponding to the tubes F-1 and F-2, and further reflecting members 79 and 81, corresponding respectively to the reflecting members 19 and 21. To this structure is added on the lower side a system of louvers in the form of a grill comprising plates 82 running longitudinally and plates 83 running transversely. These plates, it will be observed, are disposed generally in the direction of the light flux, whereby their obstructive effect is a minimum.

By the use of such a system of louvers, glare to an observer positioned beneath the fixture is almost entirely eliminated, and, further, absorption of light is reduced. For instance, from Figure 4 it will be seen that light from tube F-1 can reach tube F-4. The louver system just described would prevent this.

It will be readily understood that while the fluorescent tubes have been described as parallel to the ceiling that the aims of my invention might also be obtained by positioning of the tubes otherwise. For example, the tubes of each of the groups, say F-1 and F-2, might be positioned at right angles to their positions as shown in the illustrative embodiment. While the dimensions and appearance of the fixture would be changed, the asymmetric character of the light distribution would be more or less retained. Obviously instead of using two tubes in each of the groups of tubes, the purposes of my invention would also be served by using less than that number or more than that number.

It will further be clear that the fixture is also adapted for use as a wall bracket, the indirect illumination in this case being obtained by reflection from a wall instead of a ceiling.

While I have herein disclosed illustrative embodiments of my invention, it will be understood that my invention may be embodied in many other forms, as will be obvious to those skilled in the art, without departing from the spirit thereof. It will further be understood that the disclosure made herein of details of construction is by way of illustration merely and is not to be interpreted in a limiting sense, and that I do not intend limiting myself other than as called for by the prior art.

Having thus described my invention and illustrated its use, what I now claim as new and desire to secure by Letters Patent is:

1. A fluorescent tube lighting fixture comprising a canopy and a pair of spaced apart brackets

carried thereby for supporting two pairs of fluorescent tubes in V-formation with the axes of each pair lying in a plane inclined to the horizontal and at an angle to the plane of the axes of the other pair to give the aforementioned V-formation and a substantially diamond shaped reflecting member mounted between the tubes of each pair to present a pair of opposed apices in the said inclined plane of the axes of the pair of tubes between which it is positioned and substantially bridging the space between said pair of tubes whereby the luminous flux from said tubes striking said reflecting member will be divided into two portions one of which will be directed generally upwardly and outwardly of the fixture, while the other one will be directed oppositely to said upwardly directed portion of the luminous flux, and an elongated reflector laterally concave in cross-section mounted above the upper one of said tubes in parallel relation thereto and serving to reflect a portion of the light thereof downwardly.

2. In a fluorescent tube lighting fixture: a canopy and a pair of spaced apart brackets carried thereby for supporting two pairs of fluorescent tubes in V-formation with the axes of each pair lying in a plane inclined to the horizontal and at an angle to the plane of the axes of the other pair to give the aforementioned V-formation and a substantially diamond shaped reflecting member mounted between the tubes of each pair and presenting a pair of opposed apices in the inclined plane of the axes of the pair of tubes between which it is positioned and substantially bridging the space between said pair of tubes whereby the luminous flux from said tubes striking said reflecting member will be divided into two portions one of which will be directed gen-

erally upwardly and outwardly of the fixture, while the other one will be directed oppositely to said upwardly directed portion of the luminous flux, and an elongated reflector downwardly concave in cross-section mounted above the upper one of said tubes in parallel relation thereto and serving to reflect a portion of the light thereof downwardly.

3. A fluorescent tube lighting fixture comprising a canopy and a pair of spaced apart brackets carried thereby for supporting two pairs of fluorescent tubes in V-formation with the axes of each pair lying in a plane inclined to the horizontal and at an angle to the plane of the axes of the other pair and a reflecting member mounted between the tubes of each pair, said reflecting member being of substantially quadrilateral cross-section with a pair of opposed apices lying in the plane of the axes of said pair of tubes and substantially bridging the space between said tubes whereby the luminous flux from said tubes striking the said reflecting member will be divided into two portions one of which will be directed generally upwardly and outwardly of the fixture, while the other one will be directed oppositely to said upwardly directed portion of the luminous flux, an elongated reflector laterally concave in cross-section mounted above said brackets in parallel relation to the tubes mounted therein and serving to deflect a portion of said upwardly directed flux laterally outward of the fixture, and an elongated reflector downwardly concave in cross-section mounted above the upper one of said tubes in parallel relation thereto and serving to deflect a portion of the light of said tube downwardly.

MORRIS B. BECK.
